UNITED STATES PATENT OFFICE.

WILLIAM MEYER, OF CHICAGO, ILLINOIS.

X-RAY-CONTROL DEVICE.

1,161,238.

Specification of Letters Patent.

Patented Nov. 23, 1915.

Application filed March 15, 1915. Serial No. 14,318.

To all whom it may concern:

Be it known that I, WILLIAM MEYER, a citizen of the United States, residing at Chicago, in the county of Cook and State 5 of Illinois, have invented a certain new and useful Improvement in X-Ray-Control Devices, of which the following is a full, clear, concise, and exact description, reference being had to the accompanying drawings, 10 forming a part of this specification.

My invention relates to X-ray control devices.

More particularly it relates to a circuit having various improved control devices 15 therein which are adapted to govern and regulate the primary circuit, both as to the intensity of the X-ray discharge and also as to the time of exposure of a patient to the rays.

20 My present invention may be considered as an improvement upon that set forth in my copending application, Serial No. 8,214, filed February 15th, 1915.

The object of my invention is to produce 25 novel, efficient and simplified means of controlling X-ray circuits, whereby the operator will at all times have a one hand control of the X-ray and associated apparatus.

In carrying out an X-ray operation, the 30 two most important factors for the operator to determine are, the intensity of the X-ray discharge and the time of exposure of the patient to the same. Before he exposes the patient thereto, the operator must determine, by trial, the proper amount of resistance 35 to cut into the primary circuit to produce the desired intensity of discharge, and during these trials it is necessary for him to hold closed a controlling circuit, which, in 40 turn, closes the primary circuit. Hence when the control circuit closer and the resistance regulator are placed some distance apart on the switchboard, as is the case with the devices of the prior art, the operator

45 is greatly inconvenienced by the necessity of holding the control circuit closed with one hand and adjusting the rheostat with the other. Often it is necessary for the operator to spend a long time in thus determining the proper amount of resistance 50 to use for the actual operation, and in such cases the double control above referred to becomes particularly irksome. I do away with these difficulties by placing all the

control devices in one instrument, so that 55 the operator is enabled to make his preliminary trials and set the devices in operation with the greatest simplicity and convenience.

The accompanying drawing, which forms a part of this specification, is a diagrammatic representation of an embodiment of 60 my invention.

The apparatus represented in the figure consists essentially of a switch 1 in the primary circuit, an electro-magnet 2 controlling 65 the switch 1, a time-controlled element 3, and a connection between the electro-magnet 2 and the time-controlled element, and a controlling circuit 4 having an automatic switch 5, a regulating rheostat 6 in the primary circuit, which rheostat has a push-button 7 in the handle thereof, to open and close the control circuit 4. The time-controlled element 3 forms no part of the present invention and will therefore be described briefly as follows: The dash-pot 8 has a plunger 9 slidably mounted therein, said plunger bearing a stem 10 which is provided with suitable graduations, as indicated in the drawing. A handle 11 is provided for raising this plunger to any desired position in order to cause the graduations to register with the indicating mechanism, which comprises a sliding bar 12 which engages the notches in the stem 10. 70 The bar 12 is held against the stem 10 by the tension of the spring 13, the bar being slidably mounted in the posts 14-15. The brake 12 is provided with a slot 16, in which plays the short end 17 of a lever arm 18, which is pivoted at 19 and connected at 20 with a plunger 21 of the solenoid 2. The stem 10 of the time-controlled device is provided with a projection 23, which consists of a collar surrounding a plunger. 75 This collar engages a spring 24, which forms part of the automatic switch 5.

The switch 1 of the primary circuit has a cup 25 having mercury in the bottom thereof, and a plunger 26, to which is connected 80 the other side of the primary circuit. The plunger 26 is insulated from but mounted upon the core 21 of the electro-magnet 2, and is adapted to be moved into engagement 85 with the mercury in the bottom of the cup 25 when the electro-magnet 2 is energized. In series with the primary circuit is placed 90 the regulating rheostat 6, having contact

segments 27, between which the resistances 28 are connected. The rheostat 6 is provided with a hollow handle 29, in which slides the push button 7 mounted upon a 5 stem 30, which stem abuts against a spring contact 31, which is secured to but insulated from the rheostat contact arm. Insulated from the spring contact 31 is a similar spring contact 32, having its end bent upwardly in the direction of the contact 31. These two springs are normally held out of 10 contact by means of the insulation 33, but pressure upon the button 7 makes a contact between them. An extension cord 36 bearing auxiliary contacts 37-37 is placed in the circuit so that the operator may close the circuit when at some distance from the switchboard. These two spring contacts 15 form the first elements in the controlling circuit 4, which, when the parts are in the positions shown in the drawing, is connected from the contact 31 through the electro-magnet 2, through the battery 34 and switch 35, to the automatic switch 5 and thence to 20 the other contact spring 32. An ammeter 39 having a shunt 40 is also placed in the primary circuit. The switch 35 provides a means for cutting out the automatic switch 5 when it is desired to close the primary 25 circuit of the X-ray apparatus for any considerable length of time. When the switch 35 is thrown upon its alternate contact the automatic switch 5 will be included in the 30 circuit and the automatic timing element 3 will then become operative to open the circuit of the primary at the end of any predetermined interval of time.

Before the exposure is made the operator 35 must decide the necessary intensity of the X-rays and also the time of exposure, these 40 being the two most important details of the operation. To set the apparatus for any desired time the operator merely has to lift the plunger and locate the proper graduation 45 opposite the brake arm. To make a setting for X-ray intensity, however, there is no such simple method and the operator finds it necessary to close the control circuit, (the double throw switch 35 having 50 been placed on the T element so that the timing device is not in operation) thereby closing the primary so that he may regulate the resistance therein by means of the rheostat and noting the readings of the ammeter 55. The push button which governs the control circuit has to be continually depressed in order to keep the primary circuit closed, and thus the locating of the push button in the rheostat handle is a great convenience 60 to the operator for he is enabled thereby to keep the circuits closed and regulate the rheostat with one hand. An extension push button is also provided so that the operator may leave the switchboard and still have 65 control of the circuits. The proper amount

of resistance having been determined by the cut and try method, as indicated by the ammeter readings, the operator is ready to subject the patient to the X-ray.

If it is desired to use the automatic timing control, the switch 35 is placed upon the alternate contact marked A. The stem 10 is then raised by means of the handle 11 until the desired graduation comes opposite the end of the brake 12. This stem may be 70 graduated in any preferred manner, but I have here shown it as being graduated in 0.2 of a second. The stem 10 is held in raised position by the brake 12 until the energization 75 of the electro-magnet 2 occurs. The operator may make any adjustment desired with the rheostat handle 6 before the starting of the timing device, but when he depresses the push-button 7 in the handle 29 of the rheostat, contact is made between the springs 80 31-32 and the electro-magnet 2 is energized. When this occurs the contact 26 plunges into the mercury cup 25 and the primary circuit is closed. At the same time the brake lever 18 throws off the brake 12 85 and releases the stem 10, which is then free to fall. At the expiration of the predetermined time the collar 23 will engage the spring 24 of the automatic switch 5 and thus disengage it from the stationary contact 90 37. The controlling circuit 4 is thereby broken and the plunger 21 of the electro-magnet 2 is raised, breaking the contact of the primary at the mercury cup 25. If 95 it is desired to close the X-ray circuit for 100 a period longer than that covered by the dropping of the timing plunger, the switch 35 may be moved to the position shown in the drawings, in which the automatic switch 5 will be cut out from the controlling circuit 105 and the push-button 7 will hold the controlling circuit, and thereby the main circuit, closed as long as it is depressed.

It is to be noted that when the automatic switch 5 is in circuit the push-button 7 is 110 depressed until the circuit has been broken at the switch points 24 and 37 by means of the time element.

I have found that the placing of the push-button 7 and the resistance regulator 6 in 115 one compact mechanism not only provides a simpler design, but a much more efficient means of regulation, for the operator has under the control of one hand, all the devices which co-act to produce the proper 120 X-ray operation.

It is obvious that the same principle of operation may be involved in controlling a normally-closed circuit as well as the open circuit which I have described and illustrated.

It is to be noted that the above-described embodiment of my invention is in the form which I prefer to construct it, but I do not desire to be bound to such specific details 130

for it is obvious that changes and modifications of the same will at once suggest themselves to those skilled in the art, and it is my desire that these changes or modifications be considered as coming within the spirit and scope of the appended claims.

What I claim as new and desire to secure by Letters Patent is as follows:

1. In X-ray control devices, a normally-open working circuit, variable resistances in said working circuit, a control circuit for said working circuit, and mechanism for closing said control circuit to close said working circuit and for varying the resistance of said working circuit, said mechanism comprising two manually moving parts having a common movement, one part movable in one path for varying said resistance and the other part movable in a path substantially at right angles thereto to close said control circuit.
2. In X-ray control devices, a working circuit including a plunger, a mercury cup and a variable resistance, an electro-magnet controlling said plunger, a control circuit for said electro-magnet, a switch for closing said control circuit, and common means for operating said switch and varying said resistance.
3. In a control device, a normally-open working circuit variable resistances in said circuit, a control circuit for closing said

working circuit, a normally-open switch in said control circuit, movable means for varying said resistance in said working circuit and means carried by said movable means for closing said switch in said control circuit.

4. In an X-ray device, a working circuit, a rheostat in said working circuit having a movable resistance-varying contact, a handle for said movable contact, a control circuit for said working circuit, a pair of normally-open contacts for said control circuit, said contacts being carried by said movable contact on said rheostat, and manual means for closing said normally open contacts from said rheostat contact handle.

5. In an X-ray control device, a primary circuit and a control circuit therefor, said primary circuit having a rheostat therein for regulating the intensity of the X-ray discharge, a movable contact arm for said rheostat, a handle for said contact arm, a pair of normally-open contacts for said control circuit carried by said movable arm, and a push-button in said rheostat handle for closing said normally-open contacts.

In witness whereof, I hereunto subscribe my name this 11th day of March A. D. 1915.

WILLIAM MEYER.
